CARBURETOR

Don Cole, Evanston, Ill.

Application August 7, 1930, Serial No. 473,713

1 Claim. (Cl. 123—179)

This invention relates to automobile control devices and more particularly has reference to means for automatically opening the throttle by the operation of the starter pedal.

As the conventional accelerator pedal in an automobile, when not depressed, normally holds the throttle of the carburetor closed, it is generally necessary in starting the engine to slightly open or "crack" the throttle by the manual manipulation of a hand lever on the steering wheel. This operation is often overlooked even by experienced drivers and makes the starting of the engine difficult, if not impossible. And even if not overlooked, it always constitutes an additional operation in starting which it is desirable to eliminate.

An object of my invention is to obviate the necessity of manually "cracking" the throttle in starting by hooking it up with the starter pedal so that it will be automatically cracked whenever the starter pedal is operated.

With this and other objects in view, which may be incident to my improvements, my invention consists in the combination and arrangement of elements hereinafter described and illustrated in the accompanying drawing which shows in outline the side elevation of a conventional automobile engine with my improvements attached.

In the drawing, 1 denotes the chassis of an automobile upon which is mounted an engine 2, a starting motor 3 and floor board 4. Protruding through holes in the floor board 4 are the conventional accelerator pedal 5 and starter pedal 6. Pedal 5 is pivotally connected to a rocker arm 7 mounted upon chassis 1 and also to a rod 8 which in turn is pivotally attached to throttle lever 9 of a carburetor 10, so that when pedal 5 is depressed, throttle 10 is opened in the usual way. A spring 11, attached at one end to arm 7 and anchored at its other end to chassis 1, keeps pedal 5 in its uppermost position and throttle 10 normally closed.

Similarly, pedal 6 is pivotally connected with a rocker arm 12 mounted upon chassis 1 and articulated with link 13 to rocker arm 14 which is so mounted upon chassis 1 as to engage starting but-

ton 15 of starter 3 whenever pedal 6 is fully depressed. A spring 16, attached at one end to arm 12 and anchored at its other end to chassis 1, normally keeps arms 12 and 14 and pedal 6 in their uppermost position. Pivotedly connected to arm 12 is a slotted lost-motion link 17 having an adjustable screw 18 which engages a pin 19 on the end of pedal 5 whenever pedal 6 is depressed and pedal 5 is not depressed. By this arrangement, every time pedal 6 is depressed for starting the engine, link 17 pulls arm 7 to the left with arm 12 and automatically cracks the throttle of carburetor 10. Adjustable screw 18 fixes the amount of throw of arm 7 with respect to arm 12 and thus determines how much the throttle will be cracked by the operation of starter pedal 6. As soon as pedal 6 is released, spring 16 returns it and arm 12 to their uppermost positions and the slot in link 17 then permits the normal operation of the throttle by accelerator pedal 5.

While I have shown and described the preferred embodiment of my invention, I wish it to be understood that I do not intend to limit myself to the constructional forms shown by way of illustration, as changes in combination and arrangement of elements may be made by those skilled in the art without departing from the spirit of my invention or exceeding the scope of the appended claim.

I claim:

In a control device for an internal combustion motor, a carburetor throttle, a foot-operated jointed accelerating member connected to the throttle, a supporting member having one end connected to the joint of the accelerating member and its other end pivoted to a fixed point, a manually operable starter member, and a member pivoted to the starter member and having an elongated slot embracing said joint to form a lost motion connection between the accelerating member and the starter member so constructed and arranged that actuation of the starter member opens the throttle slightly but the starter member when in released position does not affect the operation of the accelerating member.

DON COLE.
